(57) **CLAIM**

The ornamental design for a light guide for narrow aperture luminaire as shown and described.

DESCRIPTION

FIG. 1 is a top perspective view of a light guide for narrow aperture luminaire;

FIG. 2 is a front view;

FIG. 3 is a rear view;

FIG. 4 is an end view;

FIG. 5 is a top view; and,

FIG. 6 is a bottom view.

The broken lines shown in FIGS. 1, 2, 3 and 5 represent portions of the light guide for narrow aperture luminaire that form no part of the claimed design. The light guide for narrow aperture luminaire is shown with a symbolic break indicating the end of the claimed portion of the light guide for narrow aperture luminaire.
